UNITED STATES PATENT OFFICE.

FRANCIS G. HYKE, OF ST. LOUIS, MISSOURI, ASSIGNOR TO HYKE BROS. MFG. CO., OF ST. LOUIS, MISSOURI, A CORPORATION OF MISSOURI.

WINDOW-REFRIGERATOR.

1,245,351.

Specification of Letters Patent.

Patented Nov. 6, 1917.

Application filed November 19, 1913. Serial No. 801,952.

To all whom it may concern:

Be it known that I, FRANCIS G. HYKE, a citizen of the United States, residing at the city of St. Louis and State of Missouri, have 5 invented a new and useful Window-Refrigerator, of which the following is a specification.

This invention relates to refrigerators, and it consists of a receptacle having its 10 walls separably engaged or interlocked whereby the receptacle may be taken apart when not in use.

An object of the invention is to produce a receptacle comprising inclosing walls provided with means whereby the walls may be interlocked at will to assemble the receptacle, or detached in order to enable the receptacle to be disassembled.

Another object is to provide a receptacle 20 adapted to be positioned within a window or wall opening, and provided with means for supporting articles therein, and with means for supporting the receptacle within the window or opening where it is positioned.

Another object is to provide a receptacle adapted to be employed to serve the purpose of a refrigerator in windows or wall openings, and composed of metallic walls provided with detachable interlocking devices 30 so that the refrigerator may be readily detached and disassembled when not in use.

Other objects will appear from the following description, reference being made to the accompanying drawings in which I have illustrated a preferred embodiment of my present invention, and in which—

Figure 1 is a plan view of the refrigerator supported within a window frame, outside 40 of the window.

Fig. 1^a is a broken sectional view, showing a corner connection of the end and side walls.

Fig. 2 is a view looking into the refrigerator from within the room or apartment 45 from which the refrigerator extends, the window being partially raised to permit access to the contents of the refrigerator.

Fig. 3 is a sectional view on the line 3—3, 50 for instance, of Fig. 2 looking in the direction indicated by the arrow.

Fig. 4 is a detailed view of the binding or locking device whereby the top or cover of the refrigerator is fastened to or interlocked with the walls.

Fig. 5 is a cross sectional view showing the interlocked connection between the top and the walls of the refrigerator.

Fig. 6 is a detail sectional view illustrating a portion of one of the shelf supports 60 within the refrigerator, and the shelf in position thereon.

Fig. 7 is a view of the supporting blocks or devices adapted to be positioned within the window frame or opening to support the 65 refrigerator therein.

Fig. 8 is a sectional view on the line 8—8 of Fig. 7.

The side wall 1 and the end walls 2 are preferably of sheet metal of any required 70 quality, and may be of any desired size. The outer or rear edges of the end walls are bent to provide inwardly extending grooves or channels 3, the walls of the grooves or channels being integral with the end walls. The 75 ends of the side wall 1 are doubled outwardly to provide engaging projections 4 which are adapted and arranged to pass into the channels 3 and thereby form an interlocking connection between the side and end walls. The 80

side and end walls may be detached or separated from each other by raising the side wall, which operation slides the engaging projections 4 upwardly within the channels 3 until the parts are disengaged. The upper 85 edges of the end walls are bent to provide depending flanges 5, and the upper edge of the side wall 1 is bent to provide a similar depending flange 6. The top or cover 7, which is also preferably, though not essen- 90

tially, of sheet metal, is arranged to rest upon the upper edges of the end walls, and to extend over and beyond the upper edge of the side wall, substantially in the manner shown in Fig. 3. The edge of the top or 95 cover 7 which is above the side wall 1 is bent to provide a groove or channel 8 which is arranged to receive the depending flange 6, in the manner shown in Fig. 3. The bent portion of the side wall and the top or 100 cover are thus interlocked so that it is impossible to remove the top or cover except by sliding the top or cover longitudinally until the interlocking flanges pass beyond each other. The edges of the top or cover above 105 the end walls 2 are bent upon themselves to provide flanges 9. An angular member 10 fits over the corner formed by the meeting of the top and end walls, and is provided with flanges 11 which engage under the 110

flanges 5 and 9, thereby securely locking the top or cover upon the compartment or enclosure formed by the side wall 1 and the end walls 2.

8 The bottom or floor 12 of the refrigerator is preferably, though not necessarily, of sheet metal and rests upon supporting flanges 13 rigid with the inner sides of the end walls. The outer edge of the floor or bottom is provided with a depending flange 14, which 10 engages within a groove or channel formed by an upturned flange 15 at the lower edge of the side wall 1. Locking devices 16 pivotally supported by the inner side of the 15 side wall 1 engage against the floor or bottom 12, thereby firmly holding the floor or bottom seated upon the supporting flanges 13, and in interlocked engagement with side wall 1. This prevents the bottom or floor 20 from being raised, and prevents access to the contents of the refrigerator except through the open inner side, which becomes obvious by reference to Fig. 3. The inner edge of the floor or bottom 12 is provided 25 with a depending flange 17, which is straight or flush with the inner vertical edges of the end walls 2.

The end walls may be provided with parallel supporting flanges 18, at a suitable 30 distance from the top and bottom, and a shelf 19 may be mounted upon said supporting flanges. The inner and outer edges of the shelf 19 may be provided with depending flanges 20 extending downwardly 35 at opposite ends of the supporting flanges 18 to prevent movement of the shelf and to hold the shelf securely in position.

As previously mentioned the refrigerator is particularly adapted to be supported within 40 a window or opening, outside of the window, for instance. When so used the lower edges of the end walls may rest upon the lower part of the window frame, as shown in Fig. 3. The inner edges of the end walls 45 are provided with outwardly extending reinforced flanges 21 arranged to engage against the inner sides of retaining strips 22 fastened within the window frame. The lower sash of the window frame operates close to the inner edges of the end walls, and upward movement of the refrigerator 50 may be prevented by any suitable device or expedient, such, for instance, as screws or bolts 23 passing through the end walls and into the retaining blocks. Access to the 55 screws or bolts 23 is impossible from the exterior, and they may only be reached by raising the window and from the inside.

The inner edge of the top or cover 7 is 60 provided with a portion 24 which extends obliquely upwardly and inwardly, and is beaded or rolled at its upper or inner edge. The beaded or rolled inner edge of the top or cover forms close contact with the window, as shown in Fig. 3, so that it is im-

possible to reach the contents of the refrigerator from outside the window. The extended portion 24 of the top or cover constitutes an abutment to prevent the window from moving above the top or cover.

From the foregoing it will be seen that my improved refrigerator is preferably composed entirely of sheet metal, and is perfectly sanitary because all parts are non-absorbent and are easily kept clean. When 75 it is desired to position or mount the refrigerator within the window or opening it is only necessary to secure the retaining blocks or strips 22 to the window frame and then position the refrigerator outside the 80 window, and engage the retaining flanges 21 with the retaining strips. The bolts or screws 23 may then be placed in position to prevent removal of the refrigerator by any one outside the window.

85 The interlocked engagement of the different walls forming the refrigerator prevent foreign substances from entering the refrigerator. In order to disassemble the refrigerator, after its removal from the window, it is only necessary to slide the locking devices downwardly until they are disengaged from the flanges on the top and end walls, and then to slide or move the top longitudinally until it is disengaged from 90 the side wall 1; then to slide or move the side wall and end walls until the interlocking flanges 3 and 4 are disengaged. When the refrigerator is thus disassembled the different parts thereof may be placed flat upon 100 each other and will occupy a minimum amount of space, so that when the device is not in use it may be conveniently and readily stored.

To accommodate a refrigerator of a single 105 size to windows or openings of different dimensions, it is only necessary to provide more or less of the retaining strips 22, which may be fastened together, one against the other, in the manner shown in Fig. 8.

110 I have shown and described a preferred embodiment of my invention, but it is obvious that various alterations and changes may be made in the construction and arrangement of the parts without departure 115 from the spirit and scope of the invention. I do not restrict myself to identical features of construction or arrangement except as pointed out in the appended claims.

What I claim and desire to secure by 120 Letters Patent of the United States is:

1. A metallic structure including end walls, a single side wall connecting the end walls, a top covering the space included between the side and end walls, and a 125 bottom arranged within the side and end walls below the top, the meeting edges of the side and end walls being respectively formed for interlocking connection to secure the parts against other than 130

- a relatively sliding movement, the meeting edges of the top and side wall being formed for an interlocking connection to prevent other than a relative sliding movement of 5 the said parts, the meeting edges of the top and end walls having out-turned similar flanges, and a corner piece slidingly coöperating with and embracing both of said flanges to secure the said edges of the top and end walls in coöperative relation, and 10 means for fixing the bottom with respect to the side wall, outwardly extending flanges formed on the edges of the end walls remote from the side wall.
- 15 2. A metallic structure including end walls, a single side wall connecting the end walls, a top covering the space included between the side and end walls, and a bottom arranged within the side and end walls below the top, the meeting edges of the side and end walls being respectively formed for 20 interlocking connection to secure the parts against other than a relatively sliding move-
- ment, the meeting edges of the top and side wall being formed for an interlocking connection to prevent other than a relative sliding movement of the said parts, the meeting edges of the top and end walls having out-turned similar flanges, and a corner piece slidingly coöperating with and 25 embracing both of said flanges to secure the said edges of the top and end walls in coöperative relation, and means for fixing the bottom with respect to the side wall, outwardly extending flanges formed on the 30 edges of the end walls remote from the side wall, and a guard strip extending upwardly from the edge of the top, remote from the side wall.
- In witness whereof, I have signed this 40 specification in the presence of two subscribing witnesses.

FRANCIS G. HYKE.
